GOLF TEE

Raymond R. Ward, North Royalton, Ohio

Application April 12, 1950, Serial No. 9,158

Term of patent 3½ years

(Cl. D34—5)

To all whom it may concern:

Be it known that I, Raymond R. Ward, a citizen of the United States and a resident of North Royalton, in the county of Cuyahoga and State of Ohio, having invented a new, original, and ornamental Design for a Golf Tee, of which the following is a specification, reference being had to the accompanying drawings forming a part hereof.

In said drawing, Fig. 1 is a side elevational view of a golf tee showing my new design; Fig. 2 is a similar view, but looking at the golf tee from the right in Fig. 1; Fig. 3 is a top plan view; Fig. 4 is a horizontal sectional view, on the line 4—4 of Fig. 1; and Fig. 5 is a vertical sectional view, on the line 5—5 of Fig. 3.

I claim:

The ornamental design for a golf tee, as shown.
RAYMOND R. WARD.
